UNITED STATES PATENT OFFICE.

AUGUSTUS J. STANLEY, OF COLORADO SPRINGS, COLORADO.

CAR-COUPING.

SPECIFICATION forming part of Letters Patent No. 509,457, dated November 28, 1893.

Application filed August 30, 1893. Serial No. 484,388. (No model.)

To all whom it may concern:

Be it known that I, AUGUSTUS J. STANLEY, a citizen of the United States, residing at Colorado Springs, in the county of El Paso and State of Colorado, have invented certain new and useful Improvements in Car-Couplings; and I do hereby declare that the following is a full, clear, and exact description of the same, reference being had to the annexed drawings, making a part of this specification, and to the letters of reference marked thereon.

The present invention has for its object to provide an automatically operating coupling for cars in which the action of the parts when the cars come together will be more effective and certain and the operation of coupling rendered less difficult, and the invention consists in a coupling constructed substantially as shown in the drawings and hereinafter described and claimed.

Figure 1 of the drawings represent a longitudinal vertical section of a draw-head with my improved coupling, the coupling-pin and its connections also the end of the car or car-truck being shown in elevation. Fig. 2 is a transverse section taken on line xx of Fig. 1; Fig. 3 a detail view in perspective of the two jaws which are connected together and located within the draw-head; Fig. 4 a detail view in perspective of the connection between the lever and coupling-pin by which the latter is elevated to uncouple the cars.

In the accompanying drawings A represents the end of a car or car truck to which the draw-head B is suitably connected in any well known and desirable manner. The draw-head has an inclined base a and at its front a shoulder b and to the rear thereof is a semi-circular seat c which together form a support and a guide for a jaw C which is suitably pivoted within the draw-head. The jaw C has a suitable opening d for the passage of a coupling pin D when said jaw is brought to a horizontal position or parallel with the upper side of the draw-head as shown in dotted lines of Fig. 1. Connecting with the jaw C through the medium of a knuckle-joint e , is a lever-jaw E which also has an opening f to receive the end of the coupling-pin and also a mortise g to receive a suitable key F. The key F is considered of material importance in holding the jaws C E together by locking the latter men-

tioned jaw in position after the draw-heads have been coupled, thus preventing any binding of the lever-jaw against the coupling-pin 55 by said jaw moving forward and thereby keeping the pin sufficiently loose so that it may be removed at any time without difficulty.

The coupling-pin D has connected to it a link h and to this link is attached one end of 60 a fulcrum-bar G which bar is bent at an obtuse angle and has at its inner end a suitable guide i to receive a lever-rod H. This lever-rod at its outward extremity has a similar guide 65 k for the fulcrum-bar and at its inner end connects with a crank-handle I for operating it. This connection between the coupling-pin and crank-handle forms a very perfect and easily operating means for elevating the coupling pin and allowing it to automatically descend 70 without obstruction when the jaws are brought into position to have the holes therein register with each other and with the coupling-pin. The connection between the fulcrum-bar G and the lever-rod allows the bar to slide upon 75 the rod sufficiently to prevent binding of the parts or lateral strain upon the coupling-pin or the link connected thereto. The fulcrum-bar having its extensions at an angle as shown enables the coupling-pin to be more easily raised 80 and descending by gravity more readily.

The lever-jaw E in the rear of its connection with the jaw C, is provided with a tongue K which bears against the under side of the draw-head and holds the lever-jaw in a horizontal 85 position at all times by preventing it from dropping down at an angle, the jaw E being supported by the lower jaw C. The sliding lever-jaw E has a forward bearing extension l which projects beyond the front end of the 90 draw-head when the cars are uncoupled.

In the act of coupling, the bearing extension l receives the impact resulting from the cars coming together and the lever-jaw E forced farther into the draw-head as indicated by 95 dotted lines in Fig. 1. This movement of the jaw is communicated to the lower jaw C through the medium of the knuckle-joint e by which the jaws are connected with each other, and the lower jaw as the result of said action 100 moves up to a horizontal position as indicated in dotted lines, thus bringing the holes in the two jaws in line with each other and also in line with the coupling-pin. The coupling-pin

will now drop down through the holes in the jaws and through the coupling-link of the adjacent car and thus couple the cars together.

Previous to the operation above set forth, 5 the coupling-pin is supported above the interior of the draw-head by the lever-jaw upon which it rests.

Many changes or modifications in the several details of construction may be made without departing from the principle of my invention so long as they come within ordinary mechanical skill.

I claim—

- 15 1. In a car-coupling, the combination with the draw-head of a sliding lever-jaw and a pivoted swing-jaw having openings for the reception of the coupling-pin and connected together by a knuckle joint, substantially as and for the purpose set forth.
- 20 2. In a car-coupling, the combination with the draw-head thereof of two jaws, the lower one being pivoted to the draw-head and the upper one having a sliding motion and at its respective ends having extension to form 25 a bearing at the front end of the draw-head

and a supporting-tongue at the rear thereof, substantially as and for the purpose described.

3. In a car-coupling, the combination with a sliding jaw and a pivoted jaw, of a locking device for the upper one of said jaws, substantially as and for the purpose specified.

4. In a car-coupling, a draw-head having its lower side inclined downwardly and formed with a bearing-shoulder and semicircular seat, a pivoted jaw and a sliding lever-jaw connected together by a knuckle-joint, substantially as and for the purpose described.

5. A car-coupling, consisting of a draw-head, a pivoted jaw and a sliding lever-jaw located therein and connected together by a knuckle-joint, and a locking device for the lever-jaw, substantially as and for the purpose set forth.

In testimony that I claim the above I have hereunto subscribed my name in the presence of two witnesses.

AUGUSTUS J. STANLEY.
